UNITED STATES PATENT OFFICE.

WILLIAM WOLPERT AND THOMAS WOLPERT, OF LOUISVILLE, KENTUCKY.

BATH-TUB SEAT.

SPECIFICATION forming part of Letters Patent No. 732,249, dated June 30, 1903.

Application filed September 29, 1902. Serial No. 125,273. (No model.)

To all whom it may concern:

Be it known that we, WILLIAM WOLPERT and THOMAS WOLPERT, citizens of the United States, residing at Louisville, in the county of Jefferson and State of Kentucky, have invented certain new and useful Improvements in Bath-Tub Seats; and we do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to certain improvements in bath-tub seats; and it consists in the peculiar construction thereof hereinafter described, and shown in the accompanying drawings, and particularly pointed out in the 20 subjoined claims.

25 The object of the invention is to provide a seat for a bath-tub which may be produced at nominal cost, may readily be adjusted to different heights within the tub, may be instantly applied to and removed from the tub and will not injure the latter, will conduce to the comfort of the user, and may be washed and dried after it is used. This object is accomplished by the construction illustrated in 30 the accompanying drawings, in which—

Figure 1 is a perspective view of a bath-tub provided with our improved seat therefor. Fig. 2 is a plan view of the seat, and Fig. 3 is an edge view of the same.

35 The seat herein described is composed wholly of a suitable fabric—such as canvas, cloth, or other flexible material which can be washed—and except the hooks for engaging the edge of the bath-tub no metal or other 40 rigid material which would interfere with its being washed and dried and which would render it less comfortable to the user is employed in its construction, and said hooks preferably are removable in order that the 45 device may be washed with other articles without danger of tearing the latter and to the end that a single set of hooks may be employed, if desired.

1 designates the seat proper, from the four 50 corners of which extend strips 2, from which project the hooks 3 for engaging the edge of

the bath-tub. In the practical construction of the device it is intended that the seat be adjustable within the tub so as to be located near the top of the latter to serve as a seat for an adult or to be suspended a considerable depth within said tub to serve as a seat for a child or as a support for the head of an adult re-cumbent within the tub. The supporting strips 2 are made of proper length to permit 60 said adjustment and are provided at different places within their lengths with means to be engaged by the hooks, which means preferably comprise eyes 4, adapted to receive the bent securing ends 5 of said hooks, which 65 hooks are thereby so connected to said strips as to have pivotal movement relative thereto for convenience in applying the device to a bath-tub and removing it therefrom.

In order to prevent the fabric from being 70 torn by the hooks, the walls of the eyes thereof are preferably bound with metal. Ordinary eyelets answer the purpose, and when properly flattened upon the strips 2 they will not interfere with the washing of the device 75 or catch upon and tear other articles being washed at the same time. A single set of hooks may be employed, as shown in Fig. 1, said hooks being adjustable from one set of eyes to another when it is desired to adjust 80 the depth to which the seat shall project into the bath-tub, or a hook may be provided for each of the eyes. The portions of the hooks which engage the edges of the tub may be incased in a suitable material, which will protect 85 said edges of the tub against being scratched or marred. Said hooks are formed of spring metal, having their secured ends 5 bent so as to permit them to be sprung out when it is desired to remove the hooks from 90 the strips 2.

In order that the seat portion proper, 1, may be most comfortable to the user and may have requisite strength, its edges are turned under and stitched, as shown at 6 in Fig. 4, thus providing a stiffened border thereto, and the edges of said seat may be further stiffened and strengthened by the strips 2, which preferably extend continuously across said borders and are stitched thereto.

100 From the above description of the construction of our device the manner in which it is

used and its advantages will be readily apparent. Particular attention is called to its simplicity of construction, the ease with which it may be applied to a bath-tub and removed therefrom and with which it may be adjusted upon and within said tub, and the facility afforded by its construction for the keeping of it in a clean and sanitary condition. Moreover, it is much less expensive in its construction and much more comfortable to the user than any other bath-tub seat with which we are familiar.

Having thus described the invention, what we believe to be new, and desire to secure by 15 Letters Patent, is—

1. An adjustable bath-tub seat, having a seat portion, proper, and suspending portions therefor, both composed of fabric, and each of said suspending portions having a plurality of eyes, and supporting-hooks adapted to 20

said eyes and having their free ends constructed to engage the edges of the tub.

2. An adjustable bath-tub seat, having a seat portion proper, and suspending portions therefor, both composed of fabric, and each 25 of said suspending portions having a plurality of eyes, and supporting-hooks engaged with said eyes and removable therefrom, the free ends of said supporting-hooks being adapted to engage the edges of the tub, substantially as set forth and for the purposes described.

In testimony whereof we affix our signatures in presence of two witnesses.

WILLIAM WOLPERT.
THOMAS WOLPERT.
